Merrill and Brennan's
Ornamental Design for Piano Sto.
Patented May 9, 1883.

—
Merrill
John H. Brennan
by Coban, Mass.

Heriam S. Merrill and John C. Brennan, of Chicago, Ill.

Letters Patent No. 2059-Dated May 9, 1865.

Design for a Piano-stool.

The schedule referred to in the Letters Patent and making part of the same.

shall whom it may concern:

We, Leander Miller, Heriam S. Merrill and John C. Brennan, of the City of Chicago, in the State of Cook and Stat. of Illinois, have invented and produced a new and original Ornamental Design for Piano-stools, and we do hereby declare that the following is a full, clear and exact description of the same, reference being had to the annexed photographic representation thereof, forming part of this specification.

The nature of our said design consists in constructing the vertical column or support of the stool in the form of a tapering fluted pillar.

To enable those skilled in the art to understand and make use of our said design, we will proceed to describe the same in particular, making reference to the annexed photograph of the same.

A, in the said photograph represents the base of the stool, constructed in the form of a tripod or in any other of the known forms, and constitutes a part of our invention or design.

B represents the aforesaid column or pillar of the stool supported in any suitable manner upon the tripod, or its equivalent.

2

This pillar is fluted as shown, from base to capi-
tal, substantially in the same manner as architectural col-
umns, and may be provided with the technical architectural
base and capital or not as may be preferred. We consider the
base and capital shown herein as very elegant and desirable feature
in the design, but do not desire to limit our claim to the pillar
as it is provided as the fluted column is the principal fea-
ture of our design.

We claim and desire to secure by Letters Patent.

The design for Piano Stool or Bureau shown and
described.

Witness,

H. E. Clark,
G. Farmer.
